UNITED STATES PATENT OFFICE.

ERASTUS E. WINKLEY, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

MACHINE FOR SORTING SHOE-STOCK.

1,270,476.

Specification of Letters Patent. Patented June 25, 1918.

Application filed January 24, 1916. Serial No. 73,899.

To all whom it may concern:

Be it known that I, ERASTUS E. WINKLEY, a citizen of the United States, residing at Lynn, in the county of Essex and State of Massachusetts, have invented certain new and useful Improvements in Machines for Sorting Shoe-Stock; and I do hereby declare the following to be a full, clear, and exact description of the invention, such as 10 will enable others skilled in the art to which it appertains to make and use the same.

This invention relates to machines in which heel-lifts, or other pieces of shoe stock, are operated upon, and it is applicable 15 particularly to machines for sorting or grading such pieces in accordance with their mass, although some of its features are not necessarily restricted to embodiment in a grading machine.

10 The present invention is an improvement on the machine for sorting or grading pieces of shoe stock illustrated and described in Letters Patent of the United States, No. 1,234,433, granted to me July 24, 1917.

25 One object of the invention is to provide a machine of the kind in question with efficient and reliable means for transferring pieces, from the stack in which they are fed, to the carrier by which they are transferred 30 to the various instrumentalities of the machine. To this end I employ means which are adapted to hold the pieces positively and to turn them from the vertical position, which they occupy in the stack, to the horizontal 35 position which they occupy in the carrier; and I further employ a series of such devices arranged circularly so that they may operate with an intermittent rotary movement.

40 A further object of the invention is to provide a machine of the kind in question with stop-mechanism operative automatically to arrest the operation of the machine in case a piece of material is not properly placed with relation to the operating instrumentalities of the machine, and to this end I employ, in connection with the drive mechanism of the machine, a device for throwing this drive-mechanism out of operation, this 45 device being controlled by engagement with a piece of stock in case the piece is not properly positioned.

Another object of the invention is to im-

prove the devices by which the pieces of stock, after they have been sorted or otherwise acted upon, are delivered in the form of stacks ready to be removed from the machine; and to this end the invention comprises hoppers, for holding such stacks, which are adjustable in a novel and simple 60 manner to fit them to pieces of various sizes, and it further comprises positively acting means for introducing the pieces to and retaining them in such hoppers.

Another object of the invention is to improve the means by which the pieces of stock are carried to the operative instrumentalities of the machine, particularly in such a manner as to render these means operative upon pieces of various sizes without the necessity 70 of any adjustment; and to this end the invention comprises means operative to hold the pieces frictionally but firmly upon the carrier after they have been delivered thereto by the feed-mechanism, and in the position in which they are so delivered, while the pieces are being carried from the point of feeding to the point at which they are discharged from the carrier.

Other objects of the invention, and the 80 features of construction by which they are carried out, will be noted hereafter in connection with the description of the illustrated embodiment of the invention.

The preferred form of the invention, as 85 applied to sorting heel-lifts, is illustrated in the accompanying drawings, in which Figure 1 is a plan-view of a machine embodying the present invention certain parts being broken away in different horizontal planes 90 to show the construction more fully; Figs. 2 and 3 are side-elevations of the same machine, seen from opposite directions; Fig. 4 is a side elevation, on a larger scale than the preceding figures, of the feed-table and the 95 parts associated therewith; Fig. 5 is a rear end-view of the same; Fig. 6 is a plan-view of the rear portion of the feed-table, together with the lift-pickers and the means for actuating them. Fig. 7 is a plan-view of 100 a portion of the mechanism for actuating the conveyers on the feed-table; Fig. 8 is a vertical section on the line 8-8 in Fig. 6; Fig. 9 is a right-hand side-elevation of a portion of the feed-mechanism including, 105 particularly, the means for actuating the

lift-clamps and the pickers; Fig. 10 is a vertical fore-and-aft view of a portion of the feed-mechanism, showing particularly the lift-clamps, the pickers, and the picker-actuating mechanism; Fig. 11 is a rear-elevation taken approximately on the line 11—11 in Fig. 6; Fig. 12 is a partial plan-view, showing particularly the feeler of the safety-stop and the means for actuating the lift-holding fingers of the lift-carriers; Fig. 13 is a front elevation of the same parts, with the stop-mechanism broken away; Fig. 14 is a detail view showing, in plan, the means for holding the lift-holding fingers in raised position ready to be engaged with a heel-lift; Fig. 15 is a plan-view showing, in detail, the manner in which the fingers are swung into position to engage a heel-lift; Fig. 16 is a left-hand side elevation of the feeler of the safety-stop, together with the parts immediately associated therewith; Figs. 17, 18 and 19 are, respectively, a left-hand elevation, a front-elevation, and a right-hand elevation, of certain parts of the actuating mechanism of the safety-stop; Figs. 17 and 18 showing also the yielding coupling of the drive-mechanism; Fig. 20 is a plan-view of some of the parts shown in Fig. 17; Fig. 21 is a horizontal sectional view showing, in detail, the co-operative relation of the plunger and the slide of the safety-stop; Fig. 22 is a left-hand side-elevation of the same parts; Fig. 23 is a front-elevation of a part of the drive-mechanism, showing particularly the means for controlling the belt-shifter; Fig. 24 is a right-hand, side-elevation of the picker-mechanism, including part of the cam-mechanism for actuating it; Fig. 25 is a left-hand side-elevation of the same parts; Fig. 26 is a side-elevation, looking in a diagonal direction, of parts of the interior mechanism of one of the pickers; Fig. 27 shows the same parts in vertical section on a transverse section plane, looking from the rear; Figs. 28, 29 and 30 are fragmentary views, in side-elevation, of details of the picker-mechanism; and Fig. 31 is an end-view of the mechanism of one of the pickers.

50 The invention is illustrated as embodied in a machine for sorting heel-lifts, the sorting mechanism being similar, in its general construction and in the operation performed by it, to the machine disclosed in my Letters Patent No. 1,234,433, hereinbefore referred to. Accordingly, the machine will not be described herein in its entirety, but only so far as is necessary for an understanding of those parts which are novel.

55 In the embodiment of the invention illustrated in the drawings, and like the machine of the said patent, the present machine is provided with a rotary heel-lift carrier 30 in the form of a circular plate (Figs. 1 to 3) which turns upon a vertical shaft 32 at the center of the machine. The shaft 32 is journaled in frame members above and below the carrier as in my earlier machine. On this carrier the lifts are conveyed from mechanism by which they are fed singly to 70 the carrier, to and past the operative instrumentalities of the machine, and then to a series of lift-holders into which the lifts are discharged and stacked selectively according to the characteristic in accordance with 75 which they are sorted. The carrier 30 is rotated with a step-by-step movement, by mechanism which is substantially similar to the mechanism for rotating the lift picker carrier, described hereinafter and also described and claimed in my United States Patent No. 1,181,091, dated April 25, 1916. It need not, therefore, be here described. This mechanism, together with various other mechanism in the machine, is actuated by 80 cams mounted on and rotated by a horizontal cam-shaft 34 near the bottom of the machine.

85 The carrier 30 is provided with a peripheral series of lift-supports as in said application. In the former machine, however, the lifts were introduced manually to the lift-supports, while in the present machine automatic feeding means are provided for this purpose, and these means will now be 90 described.

95 The machine is provided, at the front, with a flat-topped feed-table 36 (Figs. 2 to 4) fixed at its forward end to the frame of the machine, and supported, near the rear, 100 by a brace-rod 38 extending to the base of the machine. The lifts are supported, in a horizontally arranged stack, above the feed-table, and are engaged and supported laterally, and also advanced upon the table, by 105 two endless-chain conveyers. These conveyers are mounted on two frames 40 (Fig. 5) which are seated on the top of the feed-table and are normally fixed thereon by clamp-screws 42 passing through the flanges 110 at the bases of the conveyer-frames. Each frame 40 is provided with sprocket-wheels 44 and 46 (Figs. 4 and 6) at its front and rear ends, respectively, about and upon which the conveyer-chains 48 are supported 115 in horizontal planes. Each conveyer-frame is also provided with lower and upper guard-plates 50 and 52 (Fig. 8) between which the chain moves.

120 The conveyer-chains do not directly engage the heel-lifts, but are each provided, for this purpose, with a series of abutments in the form of pointed pawls 54. As best shown in Fig. 6, these pawls are pivoted upon the chain-links, and are provided with 125 springs 56 tending to swing them outwardly from the chains. Each pawl is provided, however, with a roller 58 which engages a peripheral flange 60 (Fig. 8) on the guard-plate 50, and thus limits the outward swing 130

ing movement of the pawl. The flange 60 is narrow at the inner side of the conveyer, which permits the pawls to project beyond it into position to engage with the heel-lifts, 5 while at the outer side of the conveyer the flange is deeper and the guard-plate 52 also extends farther beyond the conveyer-chain, so that during the return-movement of the pawls, at the outer stretch of the conveyer, 10 they are entirely shielded by the guard-plates.

During the feeding operation, the series 15 of pointed pawls or abutments engage the sides of the lifts; that is, they either engage the lateral margins of the rear sides of the lifts that are directly in advance of them, or the pointed ends of the pawls coöperate with the lateral edges of the lifts to which they are immediately adjacent. The particular character of the engagement of the pawls with the lifts is entirely dependent upon the chance positions of the lifts with respect to the pawls, and is, therefore, largely accidental. Manifestly, any lift 20 may even be engaged at its rear margin on one side and at its lateral edge on the other, although the rearmost lift in the stack will probably be advanced by marginal engagement on both sides.

Whatever be the character of the engagement, each set of oppositely disposed pawls 25 functions to engage the lift in immediate proximity thereto and to advance it and the group of lifts in the stack between it and the next preceding set of pawls. Each group of lifts intermediate the several sets of pawls is, therefore, actuated independently and will remain either loosely or tightly stacked throughout the feeding operation, as the case may be; at least, until the particular group reaches a position in which it is acted upon by the pickers.

The heel-lifts are supported from beneath by a channel-shaped support 62 (Figs. 5, 6 and 8), the heel-lifts being arranged with their back-edges resting upon this support. It will be apparent that the stack of lifts is readily accessible from the top, since there are no parts above the lifts to obstruct such access (see Fig. 4), and, therefore, the operator of the machine may readily correct any derangements which may occur in the position of the several lifts in the stack, or may, if necessary, remove any lifts which are so defective as to interfere with the operation of the machine. The arrangement of the conveyer-chains and the feed-pawls is such that the operator may also introduce lifts to the stack at any time without interrupting the operation of the machine. For this purpose it is necessary merely to press the lifts forwardly upon the support 62 and between the conveyer-chains and into engagement with the rearmost lift already in the stack. When this is done, the

feed-pawls swing inwardly and yield to the introduction of the lifts, which may be tightly compacted during the filling operation, or may be loosely assembled in accordance with the manner in which they are introduced by the operator. The continuous feed of the lifts already in the stack is, however, maintained without interruption, inasmuch as the relationship of the operative pawls with respect to the stack remains substantially undisturbed. The additional lifts are at once engaged at their lateral margins or edges, as the case may be, and are advanced or fed in the manner hereinbefore described.

In order that the machine may be readily adjusted to operate upon lifts of different sizes and proportions, it is necessary to move the conveyers toward and from each other so as to vary the distance between them, it being desirable, however, that the center-line of the stack of lifts be always in the same relation to the other instrumentalities of the machine. Accordingly, means are provided for moving the conveyer-frames 40 toward and from each other in unison. For this purpose a rock-shaft 64 (Figs. 4 and 5) is journaled longitudinally with respect to the feed-table, in bearings 66 projecting downwardly therefrom. This shaft is provided, near its ends, with two pinions 68 (see full and dotted lines Fig. 4), to the forward side of each of which a pin 70 is fixed (see dotted lines Fig. 5). The pins 70 engage lugs 72 (Fig. 4) which project downwardly from the inner side of the right-hand conveyer-frame, through suitable openings in the feed-table. These lugs have vertical slots to receive the pins. At its forward end the rock-shaft 64 is provided with an arm 74, and a hand-screw 76 is threaded into the end of this arm, and projects through a slot 78 in an apron 80 depending at the rear end of the feed-table. The slot is concentric with the shaft 64, and after the lever 74 has been swung to any position permitted by the length of the slot, it may be clamped in such adjusted position by tightening the screw 76. When the shaft 64 is rocked by the action of the arm 74, the pins 70 impart a horizontal movement to the right-hand conveyer-frame 40, this movement being equal throughout the length of the frame, and after the frame has been so adjusted it may be fixed in position by tightening the clamp-screws 42.

In order that equal and opposite movements may be imparted to the left-hand conveyer-frame 40, each pinion 68 is arranged to mesh with a similar pinion 82 (Fig. 5) journaled beneath the feed-table, and the pinions 82 have pin-and-slot connections with the left-hand conveyer-frame similar to those between the pinions 68 and the right-hand frame.

It is also desirable, for reasons which will appear hereafter, to adjust the height of the lift-support 62 in changing from lifts of one size to another, and for this purpose, this support is mounted on two stems 90, which move vertically through openings in the feed-table, as shown in Figs. 4 and 3. Each stem 90 is slotted at the lower end, and engaged by the end of an arm 92, the arms 10 92 being fixed on a rock-shaft 84 journaled horizontally below the feed-table. At its rear end the rock-shaft 84 is provided with an arm 86 carrying a hand screw 88 which projects through a slot in the apron 80, as 15 shown in Fig. 5. By means of this hand-screw the shaft may be rocked and then fixed in adjusted position, so as to cause the arms 92 to support the stems 90 and, consequently, the lift-support 62 at various elevations.

As the lifts are removed one-by-one from the forward end of the stack, it is necessary to advance the stack intermittently to supply fresh lifts, and for this purpose mechanism is employed which is shown particularly in Figs. 7 and 8. Each of the sprocket-wheels 46 on which the conveyer-chains are mounted is fixed on a vertical shaft 94, which turns in a bearing-sleeve 96 in the corresponding conveyer-frame. These sleeves and shafts project downwardly, through suitable openings in the feed-table, and at the lower end of each shaft 94, a pinion 98 is fixed. Each of the 25 pinions 98 engages one of two gears 100, and these gears mesh with each other, this arrangement of pinions and gears being employed to insure that the conveyers shall always move exactly in unison, so that the feed-pawls 54 on them shall always occupy positions exactly opposite each other and thus press the lifts forwardly in normal position. Since the shafts 94 must move toward and from each other when the conveyers 30 are adjusted to feed lifts of different sizes, the pinions and gears just described are held in meshing relation by radius-links 104. The gears 100 are mounted on studs 102, which are connected with the shafts 94 by 35 links 104, while the studs 102 are connected by a link 106.

Intermittent rotation is imparted to the shafts 94 by means of automatic one-direction clutches. Each clutch comprises a disk 50 108, keyed to the corresponding shaft 90, and this disk is embraced in each case by a bifurcated arm 110, which rocks freely upon the shaft 94. Each arm 110 carries a block 112, having a recess in which a friction-roller 114 55 is carried, this roller being spring-pressed, as shown in dotted lines in Fig. 7, in a direction to cause it to pinch between the periphery of the disk 108 and the inclined bottom of the recess in the block 112, whenever the 60 arm 110 is swung in the direction indicated

by the arrows in Fig. 7. On the return-movement of the arm, the friction-roller slides freely over the disk.

During the return-movement of the feed-clutch, it is necessary to prevent retrograde movement of the shafts 94, and for this purpose a clutch-disk 116, as shown in Fig. 8, is fixed to one of the gears 100. This disk co-operates with a spring-pressed friction-roller 118 arranged to move in a recessed block 120, fixed to the connecting link 106, and these parts are arranged to permit the gears 100 to move freely in the direction of the arrows applied to them in Fig. 7 but to prevent any retrograde movement of the 75 gears.

To prevent the rocking movement of the links 104 under the influence of the retaining clutch, the upper ends of the studs 102 are seated in openings in a plate 186, which 80 is connected, by a pin 182, with one end of a distance-arm 180, the other end of the arm being connected, by a pivot 184, with the feed-table.

To impart a swinging movement to the 85 clutch-arms 110, each arm is provided with a slide-block 122 (Fig. 7), engaging a transverse slot 124 in a T-shaped yoke 126. This yoke has a longitudinal slot 128, which engages a slide-block 130 fixed to the bottom 90 of the feed-table and the yoke is thus guided to slide in the line of feed of the lifts. Movement is imparted to the slide-yoke by means of a lever 132, to which the forward end of the yoke is pivoted, this lever being mounted, at one end, on a pivot 134 beneath the feed-table. The other end of the lever 132 projects through an opening 136 (Fig. 4) in the right-hand side-flange of the table, and is connected with a rod 138 (Figs. 4 and 6). This rod slides loosely through a block 140 pivoted in the end of the lever 132, and a collar 142 is pinned to the rod so as to have positive engagement with the block in one direction of movement. A spring 144 100 is interposed between the block 140 and a collar 146 fixed at the rear end of the rod 138.

The forward end of the rod 138 is connected, by a pivot 148, with an arm 150 (Fig. 6), which is secured to a vertical sleeve 115 152 (Fig. 9). This sleeve is rotatable upon a rod 154, but is prevented from endwise vertical movement by engagement with upper and lower bearing-lugs 156 and 158, respectively, on the frame of the machine. As 120 shown in dotted lines in Figs. 4 and 9, the sleeve 152 has an interior recess 160 which receives a sleeve 162 pinned to the rod 154, this sleeve being shorter than the recess 160 so that it may slide vertically therein. The 125 sleeve 162 is provided with a rack 164, which projects outwardly through a vertical slot in the sleeve 152. The principal function of this rack will be described hereafter, but it operates, incidentally, as the means for 130

transmitting, to the sleeve 152, a rocking movement of the rod 154. This rod, as shown in Fig. 2, extends downward to a bearing in a bracket 166 on the frame of the machine, and is there provided with a bevel-pinion 168, which is splined to the rod. This pinion is in mesh with a segmental gear (not shown), on an arm 170 of a lever which is shown in dotted lines in Fig. 2. This lever 10 is pivoted on the bracket 166 and has a second arm 172, pivoted to a link 174. The link 174 is pivoted, in turn, to a cam-lever 176 which co-operates (in a manner which need not be particularly described) with 15 one of the cams on the cam-shaft 34. The operation of this cam-mechanism is to swing the lever-arm 170 and thus oscillate the pinion 168 and the rod 154 at suitable times in the operation of the machine, where- 20 by the rod 138 is moved forwardly and rearwardly so as to swing the lever 132 and thus impart movement to the chain-conveyors through the one-direction clutches above described. These movements are not posi- 25 tive in the direction of feed, but are im- panted through the spring 144 on the rod 138. The purpose of this arrangement is to permit the provision of a movement of an amplitude at least equal to the greatest 30 which may be required, in the case of the thickest heel-lifts, and to avoid the necessity of any adjustment of this amplitude for lifts of other thicknesses. Through means which will be described hereinafter, 35 the forward movement of the stack of heel- lifts is arrested automatically at the point where the endmost lift is in the proper position to be seized by the transferring means, and when the stack has been moved to this extent, further movement of the rod 138 re- 40 sults merely in compressing the spring 144. The heel-lifts are transferred, one-by-one, from the stack on the feed-table to the carrier by which they are carried to the opera- 45 tive instrumentalities of the machine, by means comprising a series of lift-pickers, four in number (see Figs. 10, 24 and 25). These pickers are generally of a type de- 50 scribed in an application for Letters Patent of the United States filed by the present inventor November 1, 1915, Serial Number 59,031, relating to blank transferring mechanism, and they are not, therefore, claimed herein except in so far as their particular 55 novel construction and mode of operation are concerned. Each picker comprises a shank 190, and three curved claws 193, which are pivotally mounted in radial slots in the outer end of the shank. These claws are 60 of such form that they may be withdrawn entirely within the slots, or swung outwardly upon their pivots, in such a manner that their sharp points may be moved into engagement with, and bury themselves in,

the face of a lift against which the picker is 65 pressed. This operation of the claws is produced by the action of a slide 192 in the form of a sleeve which surrounds the shank 190, as shown best in Figs. 26 and 27.

The slides 192 are carried in four tan- 70 getentially arranged sleeves 194, carried by a head 196 (Fig. 6) which is fixed in alinement with the stack of lifts, on the inner end of a shaft 198 journaled in a sleeve 200. This sleeve is fixed in a boss 201 on the 75 frame of the machine. A gear 202 (Figs. 6 and 9) is fixed at the outer end of the shaft 198, and this gear co-operates with the rack 164, previously mentioned as attached to the sleeve 162 on the rod 154, this rack 80 serving to impart intermittent rotation, through 90°, to the gear 202, the shaft 198 and the pickers.

The longitudinal movements of the rack 164 are produced by corresponding move- 85 ments of the rod 154, and for this purpose the rod is provided, at its lower end, with a grooved collar 206 (Fig. 2) which is en- gaged by the forked end of a lever 208 mounted on a pivot 210 on the frame of the 90 machine. This lever has a depending arm 212, which is connected, by a link 214, with a cam-lever 216. A cam-roller 218, carried by the lever 216, engages a path in a cam 220 on the shaft 34, and thus the necessary 95 rising and falling movements are imparted to the rod 154 at proper times in the opera- tion of the machine.

The rack 164 engages the gear 202 during each downward movement of the rack, so 100 as to rotate the gear in the direction of the arrow in Fig. 9, but during the subsequent rising movement of the rack, it is disengaged from the gear by the rocking movement of the sleeve 152, which has been previously de- 105 scribed, so that the rack rotates the gear only in one direction. To prevent any rota- tive movement of the gear 202 while it is not engaged by the rack 164, the sleeve 152 is provided with a locking-rack 204, which 110 is rocked into engagement with the gear by the same movement of the sleeve which dis- engages the rack 164 from the gear, and thus the sleeves 194 are held rigidly in position while the pickers in them are engaging and disengaging the heel-lifts. This type 115 of intermittent feed mechanism is not claimed specifically herein as it is claimed in my United States Patent No. 1,181,091, 120 Apr. 25, 1916, hereinbefore referred to.

After each quarter-revolution of the pick- 125 ers, they are brought to rest with one picker in a horizontal position, and its end directed toward the end of the stack of heel-lifts on the feed-table, as shown in Fig. 10, while the next preceding picker is in vertical position, with its end directed downwardly, and a heel-lift supported thereby in position

above a support, on which the lift is to be discharged as hereinafter described. With the pickers in this position, it is necessary to move their respective slides 192 so as to cause the first-mentioned picker to move into engagement with the endmost lift in the stack, and then retreat from the stack with said lift, and to cause the second mentioned picker to move downwardly, to deposit the lift held by it, and then to retreat out of engagement with said lift. To cause the movements just described, each slide 192 is provided with a bifurcated lug 222 (Figs. 10 and 26), which projects through a slot in the side of the sleeve 194 in which the slide moves. Each lug 222 is engaged by a roller 224 at one end of a lever 226 (Figs. 10 and 24), the lever being mounted, at its opposite end, to swing about a stud 228 on an adjacent sleeve 194. Each lever 226 is provided also with a roller 230, which travels in an annular slot 232 in the face of a disk 234 (Figs. 6 and 10) which is fixed on the inner end of the bearing-sleeve 200. This disk is provided with two gaps, which are normally filled by blocks 236 and 238, these blocks having slots normally continuous with the annular slot 232 in the disk, so that the rollers 230 may move freely into and out of the blocks when the pickers are rotated. When the pickers are stationary, however, as shown in Figs. 6 and 10, the rollers 230, on the levers 226 connected with the two pickers which are in operative positions, are in engagement with the blocks 236 and 238, and movement is imparted to these rollers by outward and inward movements of the blocks at this time. For this purpose, the block 236 is mounted on a bell-crank lever 240, pivoted on a fixed stud 242, while the block 238 is carried by a lever 244 pivoted on a fixed stud 246. A link 248 is pivoted to one arm of the lever 240, and to the lever 244, so that when the latter lever is swung to move the block 238, similar movements are imparted to the lever 240 and the block 236. The lever 244 is actuated by means of a rod 250 pivoted, at its upper end, to the lever, the lower end of this rod being pivoted, as shown in Fig. 2, to a cam-lever 254. This lever coöperates with one of the cams on the cam shaft 34 in a manner which need not be particularly illustrated and described, except that it will be understood that at proper times in the operation of the machine the cam-lever is actuated to move the rod 250 first downwardly, and then upwardly, thus causing the blocks 236 and 238 to swing outwardly from, and then return to, their normal positions. By these movements the blocks cause the levers 226 to swing outwardly and then inwardly, thus causing outward and inward sliding movements of the slides 192.

The interior construction of the pickers is shown in Figs. 24 to 31. A compression-spring 195, coiled around the shank 190, causes the shank to advance with the slide 192. To limit this advancing movement, however, a rod 197 (Fig. 26) is fixed to the forward end of the shank, and has a stop-lug 199 at its rear end. This stop-lug engages two stationary stops 203 and 205 (Fig. 25) located alongside the picker-head in such position as to arrest the picker in its lift-receiving and lift-discharging movements, respectively. The stop 205 is in the form of a spring-pressed plunger to cushion the shock of its engagement. The claws 193 have arms which engage a groove in a stem 207 slidable in the shank 190. A head 209 (Fig. 27) fixed to the inner end of the stem, moves in a bore in the shank. A slide 211 moves in the inner end of the bore and is retained therein by a screw cap 256. A hook 257, pivoted in the slide 211, projects through a slot in the shank 190 and engages the slide 192 at the upper end of an opening 258 therein, as shown in Figs. 26 and 27. During the advance of the slide 192, after the shank 190 has been arrested by the stop above described, the slide continues to move, compressing the spring 195, and the hook 257 and the slide 211 are thus advanced within the shank. This causes the slide 211 to engage a spring 259 supported in a sleeve on the head 209, whereby the stem is advanced, thus throwing the claws into operative position. This movement is limited by a stop-sleeve 260 surrounding the stem.

At the end of the advance of the slide 211, a spring-pressed latch 261 snaps into an opening 262 in the shank 190 and acts to retain the claws in projected position while the picker is swung into the lift-discharging position, and the slide 192 then retreats, followed by the shank after the slide has reached and engages the cap 256. During the relative movement of the slide 192 and the shank, which occurs at the beginning of this retreating movement of the slide 192, a relative movement between the slide and the hook 257 also occurs, owing to the fact that the slide 211 is retained stationary in the shank by the latch 261. From this it results that the beveled end of the hook is engaged and pressed inwardly by the end of the opening 258 in the slide 192. The hook is accordingly swung inwardly to a position in which it no longer coöperates with the slide 192, and it tends to remain in this position until restored by means hereinafter described.

Upon the next advance of the slide 192, with the picker in the discharging position, the shank 190 is advanced, and is arrested by the stop 205. The continued advance of

the slide causes it to engage the beveled end of the latch 261, whereby the latch is swung in and disengaged from the shank 190. A spring 263, interposed between the head 209 and the shank, thereupon forces the head inwardly whereby the claws are retracted and the heel-lift released. At the same time the slide 211 is forced to its original position by a spring 264 interposed between the slide 10 and the head. A dog 265 on the hook 257 is thus pressed against the cap 256, so as to swing the hook again into engagement with the slide 192.

Rotation of the shank 190 is prevented by 15 a pin 266 projecting, from the slide 192, into a slot in the shank, as shown in Figs. 26 and 28.

When a picker is pressed into engagement with the endmost heel-lift in the stack 20 on the feed-table, it is necessary to hold the stack firmly to prevent it from yielding to the pressure of the picker, particularly where the stack is so long that the elasticity of the lifts in it would permit a considerable movement under such pressure. Accordingly, means are provided for clamping the lifts near the front end of the stack, the clamping-means acting upon the edges of these lifts. As shown in Figs. 6, 10 and 30 11, two clamps 268 are arranged on opposite sides of the stack at this point, these clamps being provided with clamp-jaws 270 which are serrated on their lift-engaging surfaces. In order that the clamp-jaws may conform 35 to the inclination of the edges of the lifts, and may be adjusted to suit lifts of different forms and sizes, they have cylindrical outer surfaces engaging concave sockets in the clamp-bodies 268, and the clamp-jaws are adjustably secured in these sockets by bolts 40 272 projecting through vertical slots in the clamp-bodies.

While the lifts near the end of the stack may be clamped for the purpose described, 45 it will be apparent that the endmost lift, which is to be seized and removed by the picker, cannot be so clamped, but must be held yieldingly. Accordingly, each clamp-jaw is provided with a set of leaf-springs 50 274, seated in a slot in the face of the jaw and held therein by the bolt 272, as shown in Fig. 11, and the inner extremities of these springs are bent, as shown in Fig. 6, so as to engage the lateral edges of the endmost lift and hold this lift yieldingly, enabling 55 it to be readily withdrawn by the picker.

To guide the clamp-bodies 268 in their in and out movements, they are provided with upwardly extending arms 276, which 60 are bifurcated to engage a guide-bar 278 along which they may slide, this bar being carried in brackets 280 on the frame of the machine. To support the clamp-bodies and actuate them, they are each provided, at the 65 bottom, with a sleeve 282, and these sleeves

have threaded engagement with left-hand and right-hand screws 284 and 286, respectively, on a horizontal shaft 288 which turns in bearings on the feed-table (see Fig. 11). One end of the shaft 288 is provided with a 70 pinion 290, which meshes with a rack 292 (Figs. 2 and 4), this rack being integral with a sleeve 293 which is carried by a vertical slide-rod 294. This rod moves in bearing-lugs 298 on the frame of the machine, and it is keyed to the upper bearing to prevent it from turning. The lower end of the rod 294 is pivoted to a rod 296, near the lower end of which a sleeve 299 is 80 slidingly mounted. This sleeve is pivoted to a bell-crank lever 300, which is articulated with a cam-lever 302 pivoted on the frame of the machine. The lever 302 carries a cam-roller engaging one of the cams on the cam-shaft 34. Below the sleeve 299 a 85 collar 306 is fixed on the rod 296, and a spring 308 is interposed between the sleeve and a second collar 310 fixed on the rod. The cam-mechanism operates, at suitable times, to swing the lever 300 upwardly, thus 90 causing it, through the pressure of the spring 308, to raise the rods 296 and 294 and the rack 292. Thus the pinion 290, and the shaft 288 and the screws thereon are rotated in a direction to move the clamp-jaws 270 95 toward each other and cause them to grip the heel-lifts, this movement being arrested, when the lifts have been clamped with the requisite force. Further movement of the cam-lever 300 is absorbed by the compression of the spring 308. As soon as the endmost lift has been removed from the stack by the picker, opposite movements of 100 these parts occur, whereby the lifts are unclamped to permit the stack to be advanced 105 so as to press the next lift beyond the clamp-jaws 270 and into engagement with the springs 274.

The range of movement of the clamp-jaws 270 toward and from each other, as imparted by the mechanism just described, is only sufficient to insure that the lifts shall be properly clamped and unclamped, but when the feed-mechanism is adjusted to fit heel-lifts of different sizes it is necessary 110 to adjust the normal distance between the clamp-jaws. To permit this, the sleeve 293 is mounted on the rod 294 in such a manner that it may be swung around this rod to disengage the rack 292 from the pinion 290. For this purpose the sleeve is normally fixed 115 on the rod by a set-screw 312 (Fig. 2), and when this screw is loosened the rack may be swung out of engagement with the pinion. The shaft 288 may then be turned by means 120 of a knurled hand-wheel 314 (Fig. 11) on its outer end, so as to screw the clamp-jaws 270 toward or from each other through the required distance. The rack may then be 125 again engaged with the pinion. 130

As stated in connection with the description of the operation of the feed-conveyers, it is necessary, in advancing the stack between these conveyers, to arrest the advancing movement when the endmost lift is in position to be seized by a picker. For this purpose two abutments are employed, in the form of stop-fingers 316, shown particularly in Figs. 6, 10 and 11. These fingers constitute arms of bell-crank levers which are mounted on pivots 318, these pivots being supported by lugs 320 fixed to the feed-table. Each of the bell-crank levers is provided with a second arm 322, these arms 322 projecting toward each other and terminating in segmental gears 324, which mesh with each other and thus cause the stop-fingers 316 to have simultaneous inward and outward movements. The fingers are actuated by a link 326, connected to one of the arms 322, as shown in Fig. 11, the lower end of this link being pivoted to an arm 328, which is fixed on a rod 330. The rod slides vertically in a bearing-block 332 on the frame of the machine. A spring 334 surrounds the rod, and bears against the block 332 and against a collar 336 fixed on the rod. This spring tends to force the rod downwardly, so as to cause the stop-fingers 316 to be swung, from the position shown in Fig. 11, to a position in which they are in front of the stack of heel-lifts. The rod is normally held in the raised position of Fig. 11, however, by engagement of its lower end with a beveled surface 338 on the end of an arm 340 carried by the rocking-rod 154 (Figs. 2 and 11) and the movements, previously described, of the rod 154 are such as to cause the stop-fingers to be moved into and out of operative position at suitable times in the operation of the feed-mechanism.

The lift feeding and lift transferring mechanisms which have been explained in the foregoing description are not claimed herein, except in combination with the lift sorting mechanism, since these mechanisms form the subject matter of a divisional application Serial No. 206,784 filed December 12, 1917.

The heel-lifts are discharged by the pickers, as shown in Fig. 13, upon lift-supports in the form of flat plates 342, fixed to the lower surface of the carrier-ring 30 and projecting horizontally therefrom. Each support is provided with a central opening 344 (Fig. 12) through which the plungers which constitute the operative instrumentalities of the machine may move, as herein-after described, and the pickers are arranged to place the heel-lifts upon the supports with the middle of each lift directly over the opening 344. This accurate placing of the lifts is possible owing to the fact that the position of the lifts in the stack on the

feed-table is accurately determined by the feed-mechanism, and that the pickers seize the lifts and hold them positively until they are deposited on the supports so that the position of each lift on a support has a definite relation to the position which the lift occupied in the stack. Owing to this arrangement it is possible to use a lift-support having merely a smooth horizontal surface on which the lift is placed, this support being suitable for lifts of all sizes and shapes without the necessity of the provision of any means, adjustable or otherwise, for determining the position in which the lift is received by the support.

In order that the heel lift may be retained on the support, during the further operations of the machine upon the lift, in exactly the position in which it is delivered thereto by the picker, each lift-support is provided with a lift-holding finger 346, by which the lift is clamped frictionally upon the support (see Figs. 12 to 15). The finger is fixed to the upper end of a vertical stem 348, which slides and rocks in bearings provided by an arm 350 (Fig. 13) depending from the lift-support. This arm is integral with a base 352 which is fixed to the outer margin of the plate 342, and the base is provided also with depending lugs 354 between which a bell-crank lever 356 is pivoted. This lever has a forked end 358, which engages a reduced portion of the stem 348; and a spring 360 is connected to another arm of the lever 356 and to the arm 350. This spring tends to rock the lever in a direction to slide the stem 348 downwardly in its bearings, and thus move the finger 346 toward the upper surface of the lift-support so that it may clamp the lift upon the support by engagement with the upper surface of the lift, as shown in Fig. 15. When in its operative position, the end of the finger extends approximately to the middle of the lift, but the end of the finger is curved, as shown, to avoid interference with the operation of a pressure-pin hereinafter referred to.

In addition to the movement toward and from the lift-support, the finger must be swung into and out of a position above that occupied by the lift on the support. This is permitted by the rotation of the stem 348 in its bearings, and the inward limit of this swinging movement is determined by stop-pins 362 and 364 (Fig. 13) on the stem and the lever 356, respectively, these pins engaging each other when the finger is in its operative position. Before one of the lift-supports arrives at the lift-receiving position, as shown at the middle of Fig. 12, it is necessary that the finger be swung to its outer position, unless it happens to be already in that position, and to insure this, the finger is provided with a short arm 366,

which extends inwardly, and which when so extended may be engaged by a pin 368 (Fig. 12) arranged in its path of movement, this pin being fixed to the upper frame member of the machine which is in the form of an annular plate 370.

At the same time that the finger is swung out, as just described, it must be raised from the lift-support so as to be in position to be 10. swung, later, above the upper surface of the lift which has been delivered to the support. For this purpose a cam-block 372 (Figs. 13 and 14) is fixed on an annular frame member 374 situated below the rotary carrier 30, this cam-block being in position to be engaged by the lower end of the stem 348 of each finger as the lift-support with which that finger is associated is moved into lift-receiving position. Beyond the cam-block 20 372, and providing a continuation of its operative surface, is an arm 376 serving to retain the stem in raised position while the lift is being deposited upon the lift-support.

After the lift has been so deposited, it is 25 necessary to swing the lift-holding finger 346 into operative position above the lift, and this is accomplished by means of an arm 378 carried at the upper end of a rock-shaft 380 (Figs. 12 to 15). This rock-shaft 380 has a bearing, at its upper end, in the frame-member 370, while it extends downwardly, as 30 shown in Figs. 17 and 20, to a bearing in a bracket 382 on the frame of the machine. At its lower end the shaft 380 is provided 35 with an arm 384, which is connected, by a link 386, with a bell-crank lever 388 pivoted on the frame of the machine. This lever co-operates with a cam on the cam-shaft 34, and while this cam is not particularly illustrated, 40 it will be understood that it is formed so that, at suitable times in the operation of the machine, the shaft 380 will be rocked in a direction to cause the arm 378, at its upper end, to engage the lift-holding finger 346, as 45 shown in Fig. 12, and to swing this finger inwardly, as shown in Fig. 15, into position to rest upon the upper surface of the lift which has just been delivered. Immediately thereafter the stem 348 is released, so as to permit 50 the spring 360 to move the finger downwardly into engagement with the lift. This is accomplished by mounting the arm 376, on which the lower end of the stem rests, on a rock-shaft 396 (Figs. 13 and 14) having a 55 bearing in the frame member 374, and by providing this rock-shaft with an arm 398, carrying a pin 400 which co-operates with an arm 402 on the rock-shaft 380. The arm 402 has a wide end provided with two lugs 60 404 and 406 respectively. These lugs are so arranged that during the greater part of the rocking movement of the shaft 380 no effect is produced upon the pin 400; but

when the rocking movement by which the inward movement of the finger 346 is produced is nearly finished, the lug 404 engages the pin 400 and swings the arm 398, thus rocking the shaft 396 and swinging the end of the arm 376 away from its position beneath the stem 348, whereupon the stem 70 descends, carrying the finger 346 with it. When the shaft 380 rocks in the reverse direction, the lug 406 causes the arm 376 to be swung back into position for its next operation. 75

Since it is not permissible to have any part of the swinging movement of the lift-holding finger 346 occur while this finger is in engagement with the surface of the lift, the arm 378 is connected with the shaft 380 by 80 a lost-motion connection. For this purpose the hub of the arm is free to turn, through a limited angular space, on the shaft, but this turning movement is limited by a pin 392 which passes through the shaft and engages a stop-shoulder 394 on the hub, as shown in Fig. 13. A spring 390 is coiled about the hub, and engages the pin 392 at one end, and the arm 378 at the other end, and this spring tends to swing the arm inwardly about the shaft. After the arm has moved the finger 346 into its operative position above the lift, but before the arm 376 has been disengaged from the lower end of the stem 348, the finger engages the shank 95 190 of the picker which is in the act of depositing a lift on the lift-support, and further swinging movement of the finger is thus prevented. The rocking movement of the shaft 380 is then continued, however, sufficiently to cause the arm 402 to act as above described, this extra movement being permitted by the use of the spring-connection between the arm 378 and the shaft. 100

The operation for which the present machine is particularly adapted is the gaging of the thickness which the heel-lifts will have after they have been compressed in the manufacture of a heel, and the sorting of the lifts in accordance with their differences 110 in such thickness. For this purpose the machine is provided, as in the said Letters Patent, No. 1,234,433, with means for subjecting a limited part of the area of each lift to a predetermined pressure. These means act 115 upon each lift while it is on a lift-support in the next position in advance of that in which the lift is delivered to the support. As shown in Figs. 2, 3, and 13, the means in question comprise a plunger 408, which moves vertically through a sleeve on the frame-member 374, and a pressure-pin 410 fixed in the frame-member 370 directly above the plunger. The plunger engages the lower surface of the lift, as shown by 120 dotted lines in Fig. 12, while the pressure-pin 125

is in position to be engaged by the upper surface of the lift when the lift has been raised slightly by the action of the plunger.

The means for actuating the plunger are substantially the same as those shown in the said Letters Patent No. 1,234,433. As shown particularly in Fig. 2, this plunger is connected, by a link 412 pivoted to its lower end, with a lever 414 pivoted in a bracket 416 on the frame of the machine. The inner end of the lever 414 is forked to engage a grooved collar 418, which rises and falls at regular intervals in the operation of the machine. The means for producing this movement, and the manner in which the determination of the thickness of the lifts is rendered available in the automatic operations of the machine, will not be further described herein, as they are the same as in the machine of the said application.

Owing to the fact that the heel-lifts, after having been gaged as just described, are discharged automatically into various stack-holders according to their different characteristics, it is necessary that each lift be placed on the lift-support in a proper position for presentation to the stack holder, and this is normally accomplished, as above described, by the positive operation of the pickers. To guard against any accidental misplacing of a lift on the lift-support, and to prevent any injury to the machine, or disturbance in its operations, which might result from this cause, the machine is provided with a safety-stop which operates automatically to interrupt the movement of the machine until the misplaced lift has been removed and the machine set in operation again by the operator. The automatic operation of this stop-mechanism is controlled by a feeler which cooperates with the lift on that lift-support which is in position for the subjection of the lift thereon to the action of the plunger 408. As shown in Figs. 12, 13, and 16, this feeler comprises a plate 420, fixed upon a frame 421 which is provided with bearing lugs 422. These lugs turn loosely on a rod 424 fixed in a bracket 426 on the frame of the machine. The plate 420 is bifurcated, at its inner end, so as to clear the pin 410. It is also provided with two fingers 428, in the form of pins, which are mounted in slots 429 in the plate in position to just clear the rear edge of a heel-lift which is properly positioned on the lift-support. A third finger 430, of the same character, is also mounted in a slot in the plate, in position to just clear the breast-edge of the heel-lift. These fingers are fixed in position by nuts, as shown, engaging their screw threaded upper extremities, and upon loosening these nuts the fingers may be adjusted toward or from each other in their

slots, so as to adjust the feeler to lifts of different sizes and shapes.

The frame 421 is provided with an arm 432, to which is pivoted the upper end of the link 434. The lower end of this link is pivoted to a detent plunger 436, which slides vertically in a sleeve 437 on the frame of the machine, as shown in Figs. 19 and 22. A collar 438 is fixed on the plunger, and this collar cooperates with a lever-arm 440 which is fixed on one end of a rock-shaft 442. This shaft turns in a sleeve 443 on the frame of the machine, and the other end of the shaft is provided with an arm 444, pivoted to one end of a link 446. The other end of this link is pivoted to a lever 450. This lever is one of a series primarily adapted to serve as actuating means for a series of plungers 596, which transfer the heel-lifts from the carrier to a series of receptacles or stack-holders in connection with the automatic distribution of the lifts. This actuating mechanism is not herein described as it is fully disclosed in the said Letters Patent No. 1,234,433, but one of the levers 450 is conveniently employed in connection with the stop-mechanism, since it rises and falls at proper times to cause the arm 440 to be swung upwardly and downwardly so as to engage the collar 438, and lift the plunger 436 at suitable times. This lifting movement acts, through the link 434, to swing the feeler upwardly to the position which it occupies in Fig. 13, prior to the movement of the carrier 30 by which a lift-support with a lift on it is brought into position beneath the feeler. After the lift-support has reached this position, however, the arm 440 descends, and thus permits the feeler to fall, under the influence of gravity, so that if the lift is properly placed on the support the fingers 428 and 430 span the lift without engaging it, as shown in Fig. 12. If the lift is not properly placed, however, one or another of the fingers will engage its marginal portion, and the feeler will thus be prevented from falling to its normal position. This operation is taken advantage of, in the manner presently to be described, to cause the stop-mechanism to operate.

To permit the convenient adjustment of the feeler-fingers, as above described, it is necessary to remove the plate 420 with the fingers from its position on the frame 421. To permit this to be readily done, the plate is fastened to the frame by means of a button 425 (Figs. 12 and 16) passing through a slot 423 in the plate and normally turned to a position in which it retains the plate on the frame. The plate is prevented from shifting on the frame at this time by means of dowels 427 connecting the frame and the plate, as shown in Fig. 12. When the plate

is to be removed, the button 425 is turned into alinement with the slot 423, and the plate may then be withdrawn from beneath the frame-member 370, and disengaged from 5 the button.

The power by which the machine is driven is derived from a power-shaft 452, which is journaled in horizontal position at the top of the machine, as shown in Figs. 1, 2, and 3. 10 This shaft is provided with a fast pulley 454 and a loose pulley 456, which may be connected, by a belt 470, with any suitable source of power. At the forward end of the shaft a sprocket-wheel 458 is fixed as shown 15 in Fig. 23 and a sprocket-chain 460 connects this sprocket-wheel with a sprocket-wheel 462 at the forward end of a shaft 464 (Figs. 3 and 17) journaled horizontally in the lower part of the frame of the machine. 20 The shaft 464 carries a worm 466, which engages a worm-wheel 468 on the cam-shaft 34, and thus rotates the cam-shaft constantly while the machine is in operation.

The belt 470 is embraced by fingers 472 25 (Figs. 1 and 23) constituting parts of a belt-shipper, these fingers being fixed to a rod 474 which slides horizontally in the uprights 476 and 478 in which the power-shaft 452 is journaled. A spring 480, connected 30 with the rod 474 and with the upright 476, as shown in Fig. 2, tends to pull the rod from left to right, as shown in said figure, so as to shift the belt from the fast pulley 454 to the loose pulley 456, and thus interrupt the operation of the drive-mechanism. 35 The rod 474 is provided, however, with a handle 482 by which the rod may be pulled in the opposite direction so as to start the operation of the machine. To hold the rod 40 normally in this position, its forward end is provided, as shown in Figs. 3 and 23, with a beveled shoulder 484, adapted to coöperate with a detent 486 projecting upwardly from a lever 488. This lever is pivoted, at one 45 end, on a stud 490 projecting from the upright 478. The other end of the lever 488 is pivoted to a rod 492, and the lower end of this rod carries a pivot-pin 494 by which it is connected with a grooved block 496 (Fig. 50 19). A link 498 is pivoted to the block 496, and to a lever 500 (Fig. 18). This lever is mounted to rock on a stud 502 which is fixed in an upright 503 on the frame of the machine. A spring 504 is connected, at its 55 lower end, with the pivot-pin 494, the upper end of the spring being fixed to the frame of the machine, and this spring normally holds the rod 492, and the lever 488, in raised position, so that when the belt-shipper 60 has been moved to throw the belt on the fast pulley and start the operation of the machine, the shipper is held in this position by the detent 486 unless the operation is

interrupted either by the operator or by the action of the safety-stop. 65

The safety-stop mechanism comprises a bell-crank lever having an arm 506 which is forked and articulated with the grooved block 496, as shown in Figs. 17, 18 and 19. This lever rocks upon a stud 508 fixed in a 70 bracket 510 on the frame of the machine, and the other arm 512 (Fig. 19) of the lever depends into position to coöperate with a roller 514 mounted on a slide-rod 516. This slide-rod moves horizontally in a guide-way 518 on the frame of the machine, and is provided, near its rear end, with a block 520 fixed to the rod. A pin 522 projects from the block into engagement with a slotted link 524, this link being pivoted, at its 75 forward end, on a stud 526 in the upper end of a lever-arm 528. The arm 528 is fixed, as shown in Figs. 2 and 20, to a rock-shaft 530 journaled in bearings on the frame of the machine, and this shaft carries a second 80 arm 532. The arm 532 is connected with the cam-mechanism of the machine, in a manner which need not be particularly described, but it will be understood that the arm is rocked, at suitable times in the operation 85 of the machine, to perform the functions hereinafter described.

A spring 534 is connected, as shown in Fig. 19, with the upper end of the arm 528, and with a pin 536 on the forward end of the slide-rod 516. When the arm 528 is swung rearwardly by the cam-mechanism, this spring tends to pull the slide-rod also rearwardly, and this movement occurs at the 90 time when the feeler-plate 420 has been lowered so as to cause the feeler-fingers 428 and 430 to span the lift on a lift-support, as shown in Fig. 12. If the lift is properly placed and the feeler has descended to its 95 normal position, the detent plunger 436 will at this time have been lowered into the position shown in Fig. 22, so that the lower end of the plunger coöperates with a recess 538 in the outer end of the slide-rod 516. Accordingly the plunger at this time locks 100 the slide-rod against the rearward movement which would otherwise be imparted to it by the spring 534 and, therefore, the lever-arm 528 merely performs an idle 105 movement, stretching the spring 534 and causing the slotted link 524 to slide idly over the pin 522. If, however, one of the feeler-fingers has engaged the lift, owing to 110 faulty positioning of the lift on the lift-support, the feeler will not descend far enough to cause the detent plunger 436 to coöperate with the slide-rod. In this case the spring 534 will pull the slide-rod 516 115 rearwardly. This rearward movement causes the roller 514 to swing the lever-arm 512 rearwardly (see Figs. 3, 19, and 23) 120 125

whereby the lever-arm 506 is swung downwardly, thus pulling down the block 496 and the rod 492, and swinging the lever 488 downwardly so as to disengage the detent 5 484 from the slide-rod 474 of the belt-shipper. Thereupon the belt-shipper is drawn rearwardly by the spring 480, thus shifting the belt from the fast pulley to the loose pulley and causing the operation of the machine to cease.

It is important that a machine of the kind in question be driven by means which will yield, in case any unusual resistance is encountered to the movement of any of its parts, in order to avoid injury to the machine. Accordingly this machine is provided with yielding driving-connections, which are shown particularly in Figs. 3, 17, 18, and 20. The sprocket-wheel 462 is not 20 fixed on the shaft 464, but is fixed to a plate 542 (Figs. 17 and 20) having a hub which turns loosely on the shaft. The hub of this plate abuts against a plate 544, of which the hub 546 is keyed to the shaft. Endwise 25 movement of the sprocket-wheel and the plate 542 is prevented by engagement with the plate 544 and with a collar 540 fixed on the shaft 464. The plate 542 is provided with a stud 548 (dotted lines Fig. 18), upon 30 which a lever 550 is pivoted. This lever is provided, at one end, with a rounded boss 552, which is normally seated in a depression in the periphery of the plate 544, as 35 shown particularly in Fig. 18. The other end of the lever 550 is engaged by a compression spring 554, surrounding a plunger 556 which slides freely in an opening in the lever 550, and of which the end bears against a lever 558. The lever 558 is pivoted on a second stud 560 (Fig. 17) carried 40 by the plate 542, and it carries an adjusting-screw 562 which bears against the hub of the plate 542. The lever 558 constitutes an adjustable abutment for the spring 554, the 45 force of the spring may be adjusted so as to determine the degree of force with which the boss 552 is pressed into the recess in the plate 544. During the normal operation 50 of the machine, the rotative force is transmitted to the shaft 464, from the sprocket-wheel 462 through the plate 542 and by the yielding engagement of the boss 552 with the plate 544, and if any unusual resistance 55 or overload is encountered in the operation 60 of the machine, this connection will yield, the boss 552 riding out of the recess in the plate 544 and sliding freely over the periphery of the plate. This particular form of driving-connection is not claimed as part of the present invention, as it is disclosed and claimed in my co-pending application filed July 17, 1915, Serial No. 96,391.

It is desirable that the driving mechanism

of the machine be thrown entirely out of 65 operation whenever the yielding driving-connection operates as just described, and for this purpose there is provided, as shown in Fig. 18, an arm 564 which depends into proximity with the periphery of the plate 70 544. When the boss 552 is in its normal position, it clears the arm 564 in its revolution, but whenever it rides outwardly on the plate 544 it engages the arm 564, thus 75 swinging the lever 500 downwardly and causing the belt-shipper to operate in the manner hereinbefore described.

After the machine has gaged the lifts on the lift-supports, by the operation of the plunger 408, the lifts are discharged selectively, in the manner disclosed in the said Letters Patent No. 1,234,433, into one or another of a series of lift-holders. In the present machine, as shown Figs. 1, 2, and 3, each lift-holder comprises three vertical 85 rods 570 and 572, which are so arranged that a stack of lifts may be held between them, with the breast-edges of the lifts against the rod 570, and the rods 572 in engagement with the curved rear edges of 90 the lifts. In order that the lift-holders may be readily adjustable for use with lifts of different sizes, the rod 570 is mounted on a base-member 574 (Fig. 1) which is clamped to the frame-member 370 of the 95 machine by means of screws 576. The rods 572 are fixed in arms 578, which are connected, at their outer ends, to the member 574 by screws 579, while the inner ends of the arms 578 are connected together by a 100 screw 580. The screws 576 and the screw 580 pass through slots, as shown in Fig. 1, so that upon loosening all of the screws mentioned, the several parts may be moved relatively in such a manner as to move the 105 rods toward or from each other, and also to move them, as a whole, in or out on the frame-member 370, in such a manner as to vary the space between the rods and also to properly center this space over the positions occupied by the lifts when brought beneath the lift-holders by the operation of the carrier 30.

The stack of lifts is normally supported and retained in the lift-holder by a member 115 582 (Fig. 1) which may be designated as a "stack-retainer." The stack-retainer consists of a plate fixed on a lug 584 (Figs. 2 and 3), which is pivotally connected with the upper end of a lever 586. The lever is 120 mounted on a pivot 588 carried by a hanger 590 fixed to and depending from the frame-member 374. A spring 592, connected with the lever 586, causes the lever to remain normally in its inward position, as shown 125 in the drawing, and at this time a portion of the lug 584 rests upon a stirrup 594 fixed to and depending from the frame-member

370, whereby the stack-retainer is held in horizontal position beneath the lowermost lift in the stack.

In order that a lift may be raised from one of the lift-supports 342 which has been brought beneath a stack-holder and forced into the stack-holder, the machine is provided, beneath each stack-holder, with a plunger 596 (Fig. 1) carried by the lower frame member 374. The means for actuating these plungers are constructed and operated substantially as in the machine disclosed in the said Letters Patent No. 1,234,433, and need not, therefore, be described in this application. When the plunger rises it is necessary to have the stack-retainer 582 withdrawn from its position beneath the stack, and for this purpose the lever 586 is provided with a spring-pressed dog 598 (Fig. 3) which is in position to be engaged by a lug 602 on the shank of the plunger 596 when the plunger rises. This engagement of the dog causes the lever 586 to be swung outwardly, thus retracting the stack-retainer from the path of upward movement of the heel-lift, and this retracting movement continues until the dog swings clear of the lug, whereupon the stack-retainer is swung back to normal position by a spring 592 attached to the lever 586.

The stack-retainer is forked, as shown in Fig. 1, so that it may return into operative position while the plunger is still in elevated position, and thus the retainer is brought into position to sustain the stack before the plunger is withdrawn, and when the plunger is withdrawn the stack is lowered into engagement with the stack-retainer. When the lift is raised, as just described, from the lift-support, the lift-holding finger 346 is raised with it, so that after the lift has been added to the bottom of the stack, and the stack is then lowered upon the stack-retainer, the finger is between the lift just added and the rest of the stack. Upon the next advancing movement of the carrier 30, however, the finger is pulled out horizontally from this position in the manner already described, so that it does not interfere with the continued movement of the carrier.

The operation of the machine as a whole, except in so far as it is modified by the operation of the several novel parts hereinbefore described, is the same as that of the machine of the said Letters Patent No. 1,234,433, and need not, therefore, be described herein.

The present invention is not limited to embodiment in a machine for sorting heel-lifts, but is applicable to machines of various characters for operating, in one way or another, upon stock for boots and shoes.

It will be clear to those skilled in this class of machines and with the general ob-

jects of the present invention in view, that changes may be made in the details of structure, the described and illustrated embodiment thereof being intended as an exploitation of its underlying essentials, the features whereof are definitely stated in their true scope in the claims herewith.

What is claimed as new is:—

1. A machine for sorting shoe stock, having in combination, means for subjecting a plurality of pieces in succession to a like pressure over a portion only of their areas, a movable carrier for advancing the pieces one by one to said pressure means, means for automatically supplying said carrier with pieces, and means for automatically removing the pieces from the carrier after they have been operated upon.

2. A machine for sorting pieces of shoe stock, heterogeneous as to thickness and density, in accordance with mass, having in combination, a single means for subjecting the pieces separately and in succession to a like pressure, means for registering the thickness of each piece while under such pressure, means controlled by the registering means for sorting said pieces, and means for automatically supplying the machine with a succession of pieces.

3. A machine for sorting pieces of shoe stock, heterogeneous as to thickness and density, in accordance with mass, having in combination, means for determining the mass of the pieces comprising devices for subjecting the pieces to a like pressure over a portion only of their areas, means for utilizing the mass determination to store all pieces of like mass together, and means for automatically supplying the machine with a succession of pieces.

4. A machine for sorting pieces of shoe stock, heterogeneous as to thickness and density in accordance with mass, having in combination, means for determining the mass of the pieces comprising devices for subjecting the pieces to a like pressure over a portion only of their areas, means for utilizing the mass determination to store all pieces of like mass together, a movable carrier for advancing the pieces one by one to said pressure means, a supply station having a plurality of lifts arranged in stack formation, a picker for engaging and transferring the pieces from the stack to the carrier, and means for coöordinating the operations of the picker with the advance movement of the carrier.

5. A machine for sorting pieces of shoe stock, heterogeneous as to thickness and density, in accordance with mass, having in combination, means for determining the mass of the pieces comprising devices for subjecting the pieces to a like pressure over a portion only of their areas, means for

- utilizing the mass determination to store all pieces of like mass together, a movable carrier for advancing the pieces one by one to said pressure means, a supply station having 65
- 5 a plurality of lifts arranged in stack formation, a picker for engaging and transferring the pieces from the stack to the carrier, means for coördinating the operations of the picker with the advance movement of the 70
- 10 carrier, and means for advancing the stack lengthwise as it is depleted by the operations of the picker. 75
6. A machine for sorting shoe stock, having in combination, a supply station comprising a holder for a stack of lifts, or the like, heterogeneous as to thickness and density, a movable carrier, means for transferring the lifts singly from one end of the stack to a definite position on the carrier, and means coöperating with the carrier for grading the lifts in accordance with mass and for restacking the various grades at separate receiving stations. 80
7. A machine for sorting shoe stock, having in combination, a rotary carrier, means for rotating the carrier step by step; intermittently operating means for automatically supplying the carrier with pieces to be sorted; an upper frame member for said carrier; holders, for the pieces, sustained by said member; a frame member below the carrier; and means carried by the lower frame member for determining and indicating a characteristic of the pieces and thereafter stacking them in the holders in accordance with their similar, indicated characteristics. 85
8. A machine for sorting shoe stock, having in combination, a rotary carrier, means for rotating the carrier step by step; intermittently operating means for automatically supplying the carrier with pieces to be sorted; an upper frame member for said carrier; holders, for the pieces, sustained by said member; a frame member below the carrier, devices carried at one station on said lower frame member for determining and indicating a characteristic of the pieces; devices carried at other stations on said lower frame member for stacking the pieces in said holders in accordance with their similar, indicated characteristics, and a common actuator for said devices. 90
9. A machine for sorting shoe stock, having in combination, a rotary carrier having means at its periphery for supporting a series of the pieces, means for rotating the carrier step by step; intermittently operating means for automatically supplying the carrier with pieces to be sorted, a series of sorting stations above the path of travel of said supporting means, a holder at each of said stations for receiving the pieces 95
- from the supporting means, an initial station at the beginning of said series, devices at said initial station for determining and indicating a characteristic of the pieces on said supporting means as they are fed to said sorting stations, a series of stackers one for each holder, means for operating said stackers to push the pieces into the holders in accordance with the variations of their indicated characteristics, and means for retaining the stacks of articles in their holders. 100
10. A machine for operating on pieces of shoe stock, having in combination, a substantially flat support for a lift or the like; means for placing a lift in definite position thereon; means for operating on the lift while on the support; and means for holding the lift on the support, the holding means comprising a finger arranged to engage the lift on the opposite side from the support, and means for moving the finger toward the support, to engage it with a lift, and away from the support and also in a general direction parallel therewith to remove it from the path of movement through which the lift is applied to the support. 105
11. A machine for operating on pieces of shoe stock, having in combination, a support for lifts or the like; means for supplying a lift to the support when in a definite position; means for operating on the lift on the support in another position; a carrier for moving the support from one of said positions to the other; a lift-holding device associated and movable with the lift support, for holding the lift thereon; and means, located at the position where the lift is supplied to the carrier, and adapted, when the carrier is in that position, to coöperate with the lift-holding device to actuate the latter. 110
12. A machine for operating on pieces of shoe stock, having in combination, a support for lifts or the like; a finger for holding a lift thereon; a holder for a stack of lifts; means for moving the lift-support to and from the stack; and means for forcing the lift, on the support, into the holder, the lift-holding finger being movable with the lift from the lift-support and being withdrawn from between the lifts in the holder when the support is moved away from the holder. 115
13. A machine for operating on pieces of shoe stock, having in combination, a support for lifts or the like; a finger for holding a lift thereon; a holder for a stack of lifts; a retainer normally engaging the end of the stack; means for moving the lift-support to and from the holder; means for moving the retainer out of and into opera- 120
- 125

tive position before and after the reception of a lift; and means for forcing the lift on the lift-support into the holder.

14. A machine for operating on pieces of shoe stock, having in combination, a support for lifts or the like; a finger for holding a lift thereon; a holder for a stack of lifts; a retainer normally engaging the end of the stack; means for moving the lift-support to and from the holder; means for moving the retainer out of and into operative position before and after the reception of a lift; and means for forcing the lift on the lift-support into the holder, the retainer being arranged to span the last-mentioned means so that the retainer may be returned to operative position before the withdrawal of said means.

15. In a machine for operating on pieces of shoe stock, a holder for a stack of lifts or the like, comprising a plurality of rods adapted to engage the edges of the lifts in the stack; and means for holding the rods in parallel position, said means being adjustable to vary the space between the rods according to the size of the lifts.

16. In a machine for operating on pieces of shoe stock having a frame member provided with an opening through which a lift or the like may be passed; a holder for holding a stack of lifts above said opening, comprising a plurality of rods adapted to engage the edges of the lifts in the stack; and arms, in which the rods are fixed in parallel position, the arms being pivotally mounted on said frame member outside of said opening therein and being movable in a direction to vary the distance between the rods in accordance with the size of the lifts.

17. In a machine for operating on pieces of shoe stock having a frame member provided with an opening through which a lift or the like may be passed; a holder for holding a stack of lifts above said opening, comprising a plurality of rods adapted to engage the edges of the lifts in the stack; arms, in which the rods are fixed in parallel position, the arms being pivotally mounted on said frame member outside of said opening therein and being movable in a direction to vary the distance between the rods in accordance with the size of the lifts, means for introducing lifts to the holder through said opening, and means for retaining the lifts therein at the bottom.

18. A shoe stock sorting machine, having in combination, a plurality of holders for sorted lifts or the like, each provided with a removable lift-retainer at the bottom; a carrier adapted to support a lift and move it beneath the bottoms of said holders; means for determining and indicating a

characteristic of a lift on the carrier; and mechanism associated with each holder, for 65 retracting the lift-retainer and transferring a lift from the carrier to the holder, said mechanism being normally out of operation but being thrown selectively into operation by the indicating means.

19. An automatic machine, having, in combination, instrumentalities for operating on blanks, means for feeding blanks in succession to said instrumentalities, drive-mechanism for the machine, a feeler located adjacent the path of movement of the blanks and adapted, by engagement with the blanks, to detect an irregularity in the feed thereof, and connections, between the feeler and the drive-mechanism to interrupt the driving of 8 the machine upon such irregularity.

20. In a machine for operating on pieces of shoe stock, means for holding a stack of lifts or the like, comprising a plurality of elongated parallel members between which 85 the lifts are placed, said members engaging the edges of the lifts at a plurality of separate points; and means for adjusting said members toward and from a center line in such a manner that they may similarly co-operate with lifts of different sizes but the same form, and may hold all such lifts with their middle points on said center line.

21. A power driven machine for operating on blanks of sheet material, having in combination, driving mechanism, means for feeding the blanks one by one through the machine, a feeler mounted to reciprocate into and out of the path of the blanks, and a connection between the feeler and the 100 driving mechanism whereby any irregularity in the motion of the feeler will disconnect the driving mechanism and stop the machine.

22. A power driven machine for operating on blanks of sheet material, having in combination, driving mechanism, means for feeding the blanks one by one through the machine, a feeler mounted to move normally into and out of a position between successive 110 blanks, and a connection between the feeler and the driving mechanism whereby a curtailment of the normal movement of the feeler, for example by reason of its engagement with a blank, will disconnect the driving mechanism and stop the machine.

23. A power driven machine for operating on blanks of sheet material, having in combination, driving mechanism, means for feeding the blanks one by one through the 120 machine, a feeler provided with a plurality of fingers arranged to span the periphery of a blank, means for moving the feeler into and out of position to span a blank which is being so fed, and a connection between the 125 feeler and the driving mechanism operable

- to disconnect said mechanism if the motion of the feeler is interrupted by the engagement of one or more of its fingers with a misplaced blank.
5. 24. A power driven machine for operating on blanks of sheet material, having in combination, driving mechanism, means for feeding the blanks one by one through the machine, a feeler provided with a plurality of fingers arranged to span the periphery of a blank, said fingers being adjustable to adapt the feeler to blanks of different dimensions, means for moving the feeler into and out of position to span a blank which is being so fed, and a connection between the feeler and the driving mechanism operable to disconnect said mechanism if the motion of the feeler is interrupted by the engagement of one or more of its fingers with a misplaced blank.
10. 25. A machine for operating on pieces of shoe stock, having in combination, driving mechanism; means for operating on a lift or the like, means for presenting a lift to the operating means in a definite position; and stop mechanism controlled by engagement with the lift, operating automatically to throw the driving mechanism out of operation when the lift is not properly positioned for presentation to the operating means.
15. 26. A machine for operating on pieces of shoe stock, having in combination, driving mechanism; means for operating on a lift or the like, means for presenting a lift to the operating means in a definite position; and stop mechanism controlled by engagement with the lift, operating automatically to throw the driving mechanism out of operation when the lift is not properly positioned for presentation to the operating means, said stop mechanism comprising a feeler having parts which move into position to span the periphery of the lift when the lift is properly positioned but to engage the lift when it is not in proper position.
20. 27. A machine for operating on pieces of shoe stock, having in combination, driving mechanism; a part connected with the driving mechanism and tending periodically to move in a direction to throw the driving mechanism out of operation; a detent plunger coöperating with said part; a feeler arranged in position to engage a lift which is not properly positioned for presentation to the operating instrumentalities of the machine, said feeler being connected with said detent plunger, and means for moving the feeler periodically into and out of a position adjacent the lift, the detent plunger being moved with the feeler into and out of operative position with relation to said part connected with the driving mechanism, and the times of operation being coöordinated so

that said part is prevented from acting so long as the detent plunger is moved to operative position at the usual times.

28. A sorting machine having, in combination, a carrier for supporting and advancing a series of pieces through a plurality of stations, means for supplying pieces to said carrier at one station, means for detecting the position of each piece on said carrier and for determining a characteristic thereof at another station, and means for discharging said pieces at other stations.

29. A machine for operating upon pieces of stock having, in combination, a carrier for supporting and intermittently advancing a series of pieces, means for supplying pieces to said carrier, means for detecting the position of each piece on said carrier, means for operating upon said pieces, and means for stopping the advance of said carrier when any piece is detected in a misplaced position.

30. A machine for operating upon pieces of stock having, in combination, driving mechanism, means for supporting and intermittently advancing a series of pieces, means for placing pieces upon said support in definite positions, means for detecting any improperly positioned piece and for throwing the driving mechanism out of operation.

31. A power driven machine for operating upon pieces of stock having, in combination, a driving mechanism, a movable carrier for supporting and advancing a series of pieces, means for detecting the position of each piece upon the carrier, means responsive to said detecting means or to abnormal load conditions for throwing out said driving mechanism.

32. A power driven machine for operating upon pieces of stock having, in combination, a driving mechanism, means for successively advancing pieces through the machine, and automatic means dependent upon the position of each successive piece as it is advanced or upon abnormal load conditions for throwing out said driving mechanism.

33. A power driven machine for operating upon pieces of stock having, in combination, a driving mechanism, means for successively advancing pieces through the machine, feeling means for detecting the position of each successive piece as it is advanced past it, means for permitting the driving mechanism to yield under abnormal load conditions, means for supplying power to said driving mechanism, and means dependent upon either said feeling means or said yielding means for cutting off the supply of power.

34. A machine for grading pieces of shoe bottoming stock having, in combination,

- means for determining a mass characteristic of a piece, means for utilizing such determination to store said piece with others having a mass characteristic of like value, 5 and means for automatically supplying pieces to the machine.
35. A machine for grading pieces of shoe bottoming stock having, in combination, means for detecting the individual mass 10 characteristics of a quantity of pieces, means for sorting the pieces in accordance with their detected mass characteristics, and means for automatically supplying pieces to the machine.
- 15 36. A sorting machine having, in combination, a movable carrier for advancing a series of pieces, means for determining a characteristic of said pieces, means for sorting said pieces in accordance with said determination, means for holding a supply of 20 said pieces, a picker for successively seizing and transferring pieces from the supply to the carrier in timed coöperation with the movements of said carrier.
- 25 37. A sorting machine having, in combination, a movable carrier for advancing a series of pieces, means for determining a characteristic of said pieces, means for sorting said pieces in accordance with said determination, means for holding and intermittently advancing a supply of pieces in 30 stacked relation, a picker for successively seizing and transferring said pieces from the end of the supply stack to said carrier in timed coöperation with the movements thereof.
38. A sorting machine having, in combination, a holder for a supply of pieces, a movable carrier, means for transferring 40 pieces successively from the supply to said carrier, means for grading the pieces on said carrier, and means for stacking the pieces in accordance with their grades.
- 45 39. A sorting machine having, in combination, a carrier movable step-by-step, automatic means for supplying the carrier with pieces to be sorted, a series of holders above said carrier, means disposed beneath said carrier for determining a characteristic of 50 said pieces and delivering the pieces to the respective holders in accordance with the determinations.
- 55 40. A sorting machine having, in combination, a carrier movable step-by-step, automatic means for supplying the carrier with pieces to be sorted, a series of holders above said carrier, single means acting successively and separately upon said pieces as advanced by the carrier for grading said pieces, means 60 disposed beneath the respective holders for delivering the graded pieces thereto, and automatic means for causing the delivery means to act in accordance with the grading means.
41. A sorting machine having, in combination, a rotary carrier movable step-by-step through a supply station, a grading station and a plurality of sorting stations, means located at the supply station for automatically and successively supplying the carrier 65 with pieces to be sorted, means located at the grading station for separately and successively detecting a characteristic of the pieces as they are advanced, holding means and delivering means disposed at each sorting station, and means controlled by said detecting means for causing said delivering means to deliver the pieces to the respective holding means.
- 70 42. A machine for operating upon pieces of stock having, in combination, a movable carrier for supporting said pieces, means for holding a supply of pieces, means for transferring said pieces successively from said supply and depositing them upon the face 75 of said carrier, means for clamping said pieces in the positions in which they are deposited, and means for operating upon the pieces so held.
- 80 43. A machine for operating upon pieces of stock having, in combination, a movable carrier for supporting said pieces, means for holding a supply of pieces, means for transferring said pieces successively from said supply and depositing them upon said carrier, a rotatable and reciprocable member for firmly clamping each piece in position against said carrier, means for actuating said clamping member, and means for operating upon said pieces while so clamped. 85
- 90 44. A machine for operating upon pieces of stock having, in combination, a movable carrier for supporting said pieces, means for holding a supply of pieces, means for transferring said pieces successively from said supply and depositing them upon said carrier in definite positions, independent 95 of clamping means associated with said carrier and successively rendered operative as the several pieces are deposited upon said carrier for holding said pieces in position, and means for operating upon said pieces so held and for subsequently ejecting them. 105
- 100 45. A machine for operating upon pieces of stock having, in combination, a support 110 therefor, a holder for receiving said pieces, means for transferring said pieces from said support to said holder, a normally operative retainer associated with said holder for retaining the pieces therein, and means 115 for actuating said retainer out of and into operative position before and after the reception of each piece.
- 120 46. A machine for operating upon pieces of stock having, in combination, a support 125 therefor, a holder for receiving said pieces, means for transferring said pieces from said support to said holder, a normally operative

retainer associated with said holder for retaining the pieces therein, and means for actuating said retainer out of and into operative position before and after the reception 5 of each piece, said retainer being constructed and arranged to permit the retainer to be returned to operative position before the withdrawal of said transferring means.

47. In a machine for operating upon 10 pieces of stock, a holder for said pieces comprising a plurality of abutments adapted to engage the edges of said pieces, arms to which the abutments are secured, and means for relatively adjusting said arms to adapt 15 the holders to receive different sizes of pieces.

48. A sorting machine having, in combination, a plurality of holders for sorted pieces, a retainer associated with each holder for retaining the pieces therein, means for supporting a series of pieces and moving 20 them past said holders, means for gaging

each piece on said supporting means, means for selectively transferring each piece to the respective holders in accordance with the gaging operation, and means coöperating with said last means for retracting the corresponding retainer just prior to the transferral.

49. A machine for operating upon pieces of stock having, in combination, driving 30 mechanism, means associated with said driving mechanism tending at each cycle of the machine to throw the driving mechanism out of operation; a carrier for supporting and feeding pieces through the machine; means 35 for detecting the position of each piece upon said carrier as it is fed past a certain station; and means for preventing the operation of said means tending to throw out said driving mechanism so long as each piece 40 is properly positioned.
